UNITED STATES PATENT OFFICE.

EDMUND OCUMPAUGH, OF ROCHESTER, NEW YORK, ASSIGNOR TO DEFIANCE MACHINE COMPANY, OF ROCHESTER, NEW YORK, A CORPORATION OF NEW YORK.

CHECK-PROTECTING DEVICE.

1,160,645.

Specification of Letters Patent.

Patented Nov. 16, 1915.

Application filed July 8, 1914. Serial No. 849,643.

To all whom it may concern:

Be it known that I, EDMUND OCUMPAUGH, a citizen of the United States, residing at Rochester, in the county of Monroe and State of New York, have invented certain new and useful Improvements in Check-Protecting Devices, of which the following is a full, clear, concise, and exact description.

- 10 This invention relates to that class of devices known as check protectors, whose function is to so mark or cut checks that the amount or valuation of the check cannot be readily raised.
- 15 In one class of devices to which this invention is applicable, it is customary to mark the check by forcibly bringing against one side thereof a knurled, ridged or otherwise figured, steel cutter, the other side of 20 the check being backed by type bearing words or figures, or both, such, for example, as "Not over five hundred dollars." It has been found in practice that when the steel platen or cutter has been brought against 25 the comparatively soft type a large number of times, the type become marked or cut with lines or knurlings corresponding to those of the platen or cutter. This is not objectionable, and in fact aids in the proper 30 marking of cutting of the check paper, unless the cuts in the type become too deep or fail to properly register with the cutting edges of the platen. When the platen is faced with either knurling, diagonal straight 35 lines, or other characters, or in fact with parallel straight lines running straight across the platen from front to back, it is important that the type shall always be placed in substantially the same position under the platen 40 in order that the markings on the type, due to the cutting edges on the platen, shall always occur in the same place; otherwise the type become disfigured and eventually destroyed. When the cutting lines run 45 straight across the platen, and consequently straight around the type drum, the type becomes disfigured and eventually destroyed due to excessive hammering of the steel platen on the soft type and also due to cutting deeper at one edge of the type than at the other when the line of type is not properly centered under the plunger.

In another class of devices for marking checks and the like, to which this invention 50 is applicable, the platen is made of rubber

or other pliable material and the type are comparatively hard, and in still another class of machines both the type and the platen are made of steel or other hard material, the platen and type each being machined or otherwise manufactured so that they have registering cutting edges.

My invention is applicable to all of these types of machines and in fact to any type in which it is desirable that the type and platen shall always properly register or in which it is desirable that the force with which the platen may be brought against the type shall be limited.

One object of my invention is to prevent 70 the platen from at any time coming into contact with the soft type with undue force and to prevent the platen from coming into contact with the type at all except when the type line is properly centered under the 75 platen.

My invention also provides means for properly centering the type wheel under the platen in the operation of the device.

Other features of my invention are pointed out in the following description and claims.

The preferred application of my invention is illustrated in the accompanying drawing in which—

Figure 1 is an end view of a check-protecting device provided with my invention; Fig. 2 is a front view of the same machine; and Fig. 3 is a view of the face of cutting platen showing the diagonal cutting edges. 85

This particular embodiment of my invention comprises an inclosed casing 1, preferably made of cast metal and provided with an arm 2 carrying a plunger 3, on the lower end of which is carried the steel platen 4, 90 the cutting face of which is illustrated in Fig. 3.

Rotatively mounted within the case is a cylinder 5, about the surface of which are a plurality of lines of type, preferably spelling out the various amounts indicated on the rim of the hand-wheel 6, which is carried upon the same shaft 7 as that which carries the type wheel 5. Also secured to the shaft 7 and located one preferably at each 105 end of the type wheel 5, are wheels 8, the circumferences of which are toothed, the number and spacing of teeth in the circumference corresponding to the rows of type on the drum 5. Secured within the casing, 110

preferably one at each end thereof, are blocks 10 having openings therein within which are carried the spring-pressed plungers 11, only one of which is shown. These 5 plungers are mounted in such position that the V-shaped lower ends 12 thereof are pressed into the valleys between consecutive teeth on the wheels 8 by the springs 9, while their upper ends register with a slot in 10 the table.

As the type cylinder 5 is rotated, in order to bring different lines of type into printing position below the platen 4, the plungers 11 are reciprocated in the cylindrical openings in their carrying blocks 10, their action tending to stop the cylinder in any one of 15 its printing positions. If the cylinder is not stopped in one of its printing positions, the upper ends of the plungers 11 are forced 20 up against the underside of the check, their lengths being such that when the cylinder is in any other than a proper printing position, the ends of the platen bar 4, beyond the cutting face thereof, will engage the 25 check paper above plungers 11, one at each end of the platen, and thus either prevent the platen from forcing the paper into contact with the type wheel at all or else will cause a line of type to be properly centered 30 before the cutting operation. By means of this arrangement the cutting platen is never permitted to strike a row of type in more than one position. This maintains a corresponding marking on the face of and prevents 35 the destruction of the type. The plungers 11 also act as definite stops for the platen, thus preventing it from being forced against the type with undue pressure either when a check is inserted or when the device 40 is carelessly or roughly worked without the insertion of a check.

It is to be understood that my invention may be used in check writing or protecting machines in which there are a plurality of 45 wheels set side by side, and that a plurality of plungers, similar to 11, may be located at different positions along the cutting platen, it being preferable, under these circumstances, to omit the knurling or cutting edges 50 from the platen opposite the points at which the plungers are located, and to provide the platen at these points with a smooth surface so that checks will not be damaged when the movement of the platen is stopped 55 by reason of the projection of one or more of the plungers 11.

Although I have illustrated and described a particular embodiment of my invention, I do not wish to be unduly limited thereto, 60 many modifications and other applications of my invention being possible without departing from the spirit or scope thereof.

I claim:

1. In a check-protecting machine, the 65 combination with a rotatable type wheel, of

a platen adapted to press a sheet of paper against the type when the type wheel is in various printing positions, and means acting through the paper to prevent the platen from pressing the paper against the type when the type are under the platen but slightly out of printing position.

2. In a check-protecting device, the combination with a reciprocating cutting platen, 75 of a member carrying a plurality of lines of type any one of which is adapted to be brought into printing position beneath the platen, and means engaging the platen itself and an integral part of the movable type carrying member to prevent the cutting action of the platen unless one of the lines of type is in proper printing position under the platen.

3. In a check-protecting device, the combination with a platen having diagonal cutting lines thereon, of a type cylinder having a plurality of lines of type, any one of which may be brought into printing position beneath said platen, said lines of type having diagonal grooves therein corresponding to 90 the diagonal cutting edges of the platen, and means engaged by an integral part of the type cylinder and by the platen to prevent the latter from being brought into engagement with the type cylinder unless a line of type is in proper position under the platen so that the diagonal grooves therein will properly register with the diagonal cutting edges in the platen.

4. In a check-protecting device, the combination with a cylindrical type wheel, of 100 a member having a toothed face rotatable with said type wheel, a reciprocating member having a V-shaped portion adapted to fit into the valley between the teeth on the 105 first-named member, and a platen for pressing a check against any one of the lines of type on said type cylinder, said reciprocating member being engaged by said platen before the check is pressed against the type 110 unless said type wheel is properly positioned for printing.

5. In a check-protecting device, the combination with type, of a platen adapted to 115 press a sheet of paper against said type and a plunger in co-operative relation with the type adapted to raise the paper to prevent the platen from pressing the paper against the type whenever the type is not properly placed in printing position.

6. In a check-protecting device, the combination with type, of a platen having a cutting face and two plane smooth faces, one at 120 each end of the cutting face, and stops beneath the smooth faces, the check lying between the smooth faces and the stops.

7. A platen for check-printing machines having a plane smooth face at each end and a rough cutting face therebetween, all of 125 said faces being in substantially the same 130

plane whereby they may all engage a check without tearing it.

8. In a check-protecting device, a line of soft type, a hard cutting platen, a stop therefor to prevent the platen from striking the type when the type are out of proper alining position, and also for preventing the platen from striking the type with undue force when the typ^w are in proper alining

10 position.

9. A platen for check-protecting ma-

chines having two faces for engagement with the check, one serving as a cutting face and the other as a stopping face, the latter being smooth to prevent cutting the check. 15

In witness whereof, I hereunto subscribe my name this 16 day of June A. D., 1914.

EDMUND OCUMPAUGH.
